UNITED STATES PATENT OFFICE

159,394

COUNTER ATTACHMENT FOR FREEZER UNITS OR THE LIKE

Harry Lon Ross, New York, N. Y., assignor to Kay,
Inc., New York, N. Y., a corporation

Application December 27, 1948, Serial No. 150,364

Term of patent 3½ years

(Cl. D80—2)

To all whom it may concern:

Be it known that I, Harry Lon Ross, a citizen of the United States, residing at New York, in the county of Kings and State of New York, have invented a new, original, and ornamental Design for a Counter Attachment for Freezer Units or the like, of which the following is a specification, reference being had to the accompanying drawing, forming a part thereof.

The broken lines are for illustrative purposes only.

I claim:

The ornamental design for a counter attachment for freezer units or the like, substantially as shown and described.

HARRY LON ROSS.
